VEHICLE LUGGAGE RACK LIGHTING FIXTURE

Orval W. Rahn, Chicago, Ill.

Application December 30, 1950, Serial No. 13,632

Term of patent 14 years

(Cl. D48—20)

To all whom it may concern:

Be it known that I, Orval W. Rahn, a citizen of the United States, residing at Chicago, in the county of Cook and State of Illinois, have invented a new, original, and ornamental Design for a Vehicle Luggage Rack Lighting Fixture, of which the following is a specification, reference being had to the accompanying drawing, forming a part hereof.

In the drawing:

Fig. 1 is a bottom plan view of a vehicle luggage rack lighting fixture, showing my new design;

Fig. 2 is a side elevational view of the fixture looking at the left of Fig. 1; and

Fig. 3 is an end elevation of the fixture.

The characteristic features of my design are shown in full lines.

I claim:

The ornamental design for a vehicle luggage rack lighting fixture, substantially as shown and described.

ORVAL W. RAHN.
